REPELLING DEVICE

Paul A. Hunicke, Fort Madison, Iowa

Application February 1, 1939, Serial No. 254,101

2 Claims. (Cl. 299—95)

My invention relates to protective devices and more particularly to protective devices utilized for repelling burglars, hold-up men and other criminals.

5 One of the principal objects of my invention is to provide a protective or repelling device capable of being hidden within the clothing of a wearer, for the most part, and operable for discharging a gas or liquid to blind or otherwise 10 render the criminal helpless and preclude the latter from carrying out his purpose.

Another object of my invention is to provide a device of the character described which is simple in construction, durable in use, efficient in 15 operation and economical in manufacture.

15 Other objects and advantages will be apparent from the following description, appended claims and annexed drawing.

Referring to the drawing wherein like reference 20 characters designate like parts throughout the several views:

Figure 1 is a side elevation of my invention illustrating the same as applied to the arm of a user.

25 Figure 2 is a front elevation of my invention.

Figure 3 is a detail sectional view taken on the line 3—3 of Figure 2.

Figure 4 is a detail sectional view taken on the line 4—4 of Figure 2.

30 In practicing my invention I provide a cylindrical shaped container 5 adapted to contain a repelling gas or liquid and which is provided adjacent the upper end thereof with a hook 6 engaging the garment of the wearer adjacent the 35 sleeve aperture in the garment. The container is thus disposed adjacent the upper arm of the wearer and hidden from view.

The container, at the upper end 7 thereof, is 40 provided with an intake valve 8 for admitting gas or liquid under pressure whereby to fill said container for use, said valve being of an ordinary construction. The lower end 9 of the container has connected thereto a nipple 10 on which is secured the upper end of a tube 11, the lower 45 end of the tube extending downwardly through the sleeve of the garment and equipped with a strap 12 encircling and connected to the wearer's wrist to support the tube in proper position.

The lower end of the tube 11 has connected 50 thereto the upper end of a discharge valve 13, the latter comprising a casing 14 having an outlet passage 15 extending therethrough, the lower end of which is provided with a discharge nozzle 16. The outlet passage 15 has arranged therein a 55 valve seat 17 normally closed by a spring pressed

valve member 18. The valve member 18 is fashioned with a stem 19 extending without the casing and equipped with a push button 20 whereby said valve member may be pressed inwardly to open the valve seat and effect communication between the tube 11 and nozzle 16 through the passage 15.

In use, the container is disposed within the sleeve of the garment as illustrated in Figure 1 and the tube leading therefrom is secured to the 10 wrist by means of the strap 12. In this position the valve 13 is carried in the palm of the hand with the nozzle underlying the forefinger. Upon closing of the hand and actuating the push button by means of the thumb, the gas or liquid from the container is released and discharged into the 15 face of the criminal to render him helpless. A device of this character is particularly adaptable for bank messengers, prison guards, ladies out alone at night and other divers persons desiring 20 protection.

It is obvious that the invention is not confined to the herein described use therefor as it may be utilized for any purpose to which it is adaptable. It is therefore to be understood that the invention is not limited to the specific construction as 25 illustrated and described, as the same is only illustrative of the principles of operation which are capable of extended application in advance forms, and that the invention comprehends all 30 construction within the scope of the appended claims.

What I claim is:

1. A device of the character described, comprising, a receptacle adapted to be hidden within the sleeve of a garment of a user adjacent the upper arm of said user, a tube connected to said receptacle and adapted to extend therefrom to the palm of the hand of said user, a strap carried by said tube for securing the latter in adjusted position about the wrist of said user, a normally closed discharge valve connected to said tube and adapted to be carried within the palm of the hand and operable therein upon closing of the fingers to open position for discharging the contents of said receptacle into the face of a criminal, and a hook mounted on said receptacle and adapted to engage the garment for supporting said receptacle in hidden condition within the sleeve thereof.

2. A device of the character described, comprising, a receptacle adapted to be hidden within the sleeve of a garment of a user adjacent the upper arm of said user, a tube connected to said receptacle and adapted to extend therefrom to

the palm of the hand of said user, a strap carried by said tube for securing the latter in adjusted position about the wrist of said user, a normally closed discharge valve connected to said tube and adapted to be carried within the palm of the hand and operable therein upon closing of the fingers to open position for discharging the contents of said receptacle into the face of a

criminal, an intake valve carried by the receptacle for admitting fluid thereto for discharge by said first mentioned valve, and a hook mounted on said receptacle and adapted to engage the garment for supporting said receptacle in hidden condition within the sleeve thereof. 5

PAUL A. HUNICKE.
